PEG GAME BOARD

George Mysels, New York, N. Y.

Application May 4, 1946, Serial No. 667,313

7 Claims. (Cl. 273—95)

1

This invention relates to games of skill, and more specifically to a peg game board upon which a ring can be flipped in a manner to encircle one of the peg targets thereon.

An object of the invention is to provide a game board with a runway, an obstacle extending across the end of the runway, and a target area provided with a plurality of peg targets, the board to be used with a ring which can be propelled by flipping it with the tip of the finger in such a way as to surmount the obstacle and encircle one of the pegs.

Another object is to provide a board which can be folded when not in use to form a closed box adapted to contain the game paraphernalia.

Still another object is to provide a peg game board with an approach section and a target section, and means to vary adjustably the angle between the sections.

A further object is to provide a peg game board having an approach section hingeably joined to the target section, a portion of the hinge being adapted to form the obstacle at the end of the runway.

These and other objects are accomplished in one form of the invention by providing a peg game board having an approach section with a runway thereon and side walls on opposite sides thereof, and a target section having a plurality of upwardly extending pegs, a rotatable yoke member to support said section at an adjusted angle to the runway, two side walls and a back wall, the hinge between the sections forming an obstacle between the runway and the peg targets.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a peg game board with a ring element on a runway, said board embodying features of the invention herein.

Fig. 2 is a sectional view along the line 2—2 of Fig. 1.

Fig. 3 is a perspective view of the peg game board in folded or closed position for storing or carrying.

Fig. 4 is an enlarged perspective view of the obstacle member.

Fig. 5 is a fragmentary perspective view of a

2

modification of the invention suitable for using marbles in place of rings.

In the drawings and in the specification, in which like reference numbers designate similar parts, a peg game board 10 shown in Figs. 1 to 3 inclusive is comprised of an approach section 11 rotatably joined to a target section 12, the game being played in combination with rings or hoops 13, one of which is shown lying on the approach section.

The target section 12 has a flat base portion 17, a rear wall or back stop 18, two side walls 19 and a plurality of pegs 20. The front of the base portion 17 is provided at each of its ends 15 with extensions 21 which are connected with the obstacle or hurdle 16. The obstacle portion thus serves also as a hinge element, since a hinge pin 22 extends through the obstacle portion 16 of the approach section and the extension 21 to join the two sections together rotatably. The target section 12 is provided with a yoke portion 23 which is rotatably joined thereto by a pin 24. The pegs 20 can be arranged in any desired pattern, each peg extending from the base portion 17 at right angles. Target section 12 is provided near its rear wall 18 with a locking means 12' which holds approach section 11 in closed position when the game board is not in use. Yoke portion 23, in turn, prevents locking means 12' from accidentally opening when in closed position.

The two sections 11 and 12 can be folded to form a closed box as shown in Fig. 3.

The game board can be set up and a game of skill played thereon, as follows:

The board 10 can be opened to fully extended position as shown in solid lines in Fig. 1, or with the target section 12 in a sloping position supported by the yoke portion 23 as shown in phantom.

A ring 13 can then be propelled forward by a flip of the finger. When the ring strikes the obstacle 16, it is hurled aloft. The object of the game is to cause the ring to encircle one of the pegs 20 when it descends to the target section 12. If it is desired, the pegs can be given different score ratings depending on the relative difficulty of reaching and encircling them. While the obstacle 16 has been shown and described as being a part of the approach section, it can also be made part of the target section and can also be removed from the hingeing means, if so desired.

In the form of the invention shown in Fig. 5 target section 12' is provided with a plurality

of various size rings 20' which are placed one within the other to form grooves or openings 21'. These rings 20' may be substituted for pegs 20 when it is desired to use marbles in place of hoops when playing the game.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A game comprising an approach section having a rear bulbous hinge element, a target section having side walls overlapping said bulbous hinge element, a hinge pin passing through said target section side walls at their said overlapping portions and passing through said hinge element, hinging said sections together, said bulbous hinge element forming an obstacle between said sections, the side of said hinge element facing said approach section having a gradual slope and the side facing said target section dropping vertically, and targets supported on said target section for receiving an object propelled thereto along said approach section and over said obstacle.

2. A game comprising an approach section having a flat runway, two side walls, and a rear bulbous hinge element extending completely between said side walls and rising above said runway substantially the same height as said side walls, a target section having side walls overlapping said approach section side walls and said bulbous hinge elements, a hinge pin passing through said target section side walls at their said overlapping portions and passing through said overlapped portions of said approach section side walls and said hinge element, hinging said sections together, said bulbous hinge element forming an obstacle between said runway and said target section, the side of said hinge element facing said runway having a gradual slope and the side facing said target section dropping vertically, said target section being adapted to swing about said hinge pin to superposed relation with said approach section, thereby forming a box and targets supported on said target section for receiving an object propelled thereto along said runway and over said obstacle.

3. A game comprising an approach section having a flat runway, two side walls, the front of said runway being open, and a rear bulbous hinge element extending completely between said side walls and rising above said runway substantially the same height as said side walls, a target section having side walls overlapping said approach section side walls and said bulbous hinge element, a hinge pin passing through said target section side walls at their said overlapping portions and passing through said overlapped portions of said approach section side walls and said hinge element, hinging said sections together, said bulbous hinge element forming an obstacle between said runway and said target section, the side of said hinge element facing said runway having a gradual slope and the side facing said target section dropping vertically, said target section being slightly wider and longer than said approach section and having an end wall connecting its said side walls and closing said approach section open end when said two sections are swung about said hinge pin to superposed relation, thereby forming a box, targets supported on said target section for receiving an object propelled thereto along said runway and over said obstacle.

4. A game comprising an approach section having a flat runway, two side walls, the front of said runway being open, and a rear bulbous hinge element extending completely between said side walls and rising above said runway substantially the same height as said side walls, a target section having side walls overlapping said approach section side walls and said bulbous hinge element, a hinge pin passing through said target section side walls at their said overlapping portions and passing through said overlapped portions of said approach section side walls and said hinge element, hinging said sections together, said bulbous hinge element forming an obstacle between said runway and said target section, the side of said hinge element facing said runway having a gradual slope and the side facing said target section dropping vertically, said target section being slightly wider and longer than said approach section and having an end wall connecting its said side walls and closing said approach section open end when said two sections are swung about said hinge pin to superposed relation, thereby forming a box, targets supported on said target section for receiving an object propelled thereto along said runway and over said obstacle.

5. A game comprising an approach section having a flat runway, two side walls, the front of said runway being open, and a rear bulbous hinge element extending completely between said side walls and rising above said runway substantially the same height as said side walls, a target section having side walls overlapping said approach section side walls and said bulbous hinge element, a hinge pin passing through said target section side walls at their said overlapping portions and passing through said overlapped portions of said approach section side walls and said hinge element, hinging said sections together, said bulbous hinge element forming an obstacle between said runway and said target section, the side of said hinge element facing said runway having a gradual slope and the side facing said target section dropping vertically, said target section being slightly wider and longer than said approach section and having an end wall connecting its said side walls and closing said approach section open end when said two sections are swung about said hinge pin to superposed relation, thereby forming a box, targets supported on said target section for receiving an object propelled thereto along said runway and over said obstacle, and a yoke hinged to said target section side walls on the outside thereof and being adapted to be swung into parallelism with said target section so that it surrounds said target section end wall and the adjacent portions of said target section side walls, and being adapted to be swung downwardly to various positions to form legs for supporting said target section in inclined positions.

6. A game comprising an approach section having a flat runway, two side walls, the front of said runway being open, and a rear bulbous hinge element extending completely between said side walls and rising above said runway substantially the same height as said side walls, a target section having side walls overlapping said approach section side walls and said bulbous hinge element, a hinge pin passing through said target section side walls at their said overlapping portions and passing through said overlapped portions of said approach section side walls and said hinge element, hinging said sections together, said bulbous hinge element forming an obstacle between said runway and said target section, the side of said hinge element facing said runway having a gradual slope and the side facing said target section dropping vertically, said target section being slightly wider and longer than said approach section and having an end wall connecting its said side walls and closing said approach section open end when said two sections are swung about said hinge pin to superposed relation, thereby forming a box, targets supported on said target section for receiving an object propelled thereto along said runway and over said obstacle, a yoke hinged to said target section side walls on the outside thereof and being adapted to be swung into parallelism with said target section so that it surrounds said target section end wall and the adjacent portions of said target section side walls, and being adapted to be swung downwardly to various positions to form legs for supporting said target section in inclined positions and a latch for securing said sections in closed position, said

yoke forming locking means for said latch when said sections are in closed position.

6. A game comprising an approach section having a flat runway, two side walls, the front of said runway being open, and a rear bulbous hinge element extending completely between said side walls and rising above said runway substantially the same height as said side walls, a target section having side walls overlapping said approach section side walls and said bulbous hinge element, a hinge pin passing through said target section side walls at their said overlapping portions and passing through said overlapped portions of said approach section side walls and said hinge element, hinging said sections together, said bulbous hinge element forming an obstacle between said runway and said target section, the side of said hinge element facing said runway having a gradual slope and the side facing said target section dropping vertically, said target section being slightly wider and longer than said approach section and having an end wall connecting its said side walls and closing said approach section open end when said two sections are swung about said hinge pin to superposed relation, thereby forming a box, pins supported on said target section for receiving a ring propelled thereto along said runway and over said obstacle, a yoke hinged to said target section side walls on the outside thereof and being adapted to be swung into parallelism with said target section so that it surrounds said target section end wall and the adjacent portions of said target section side walls, and being adapted to be swung downwardly to various positions to form legs for supporting said target section in inclined positions, and a latch for securing said sections in closed position, said yoke forming locking means for said latch when said sections are in closed position.

7. A game comprising an approach section having a flat runway, two side walls, the front of said runway being open, and a rear bulbous hinge element extending completely between said side walls and rising above said runway substantially the same height as said side walls, a target section having side walls overlapping said ap-

proach section side walls and said bulbous hinge element, a hinge pin passing through said target section side walls at their said overlapping portions and passing through said overlapped portions of said approach section side walls and said hinge element, hinging said sections together, said bulbous hinge element forming an obstacle between said runway and said target section, the side of said hinge element facing said runway having a gradual slope and the side facing said target section dropping vertically, said target section being slightly wider and longer than said approach section and having an end wall connecting its said side walls and closing said approach section open end when said two sections are swung about said hinge pin to superposed relation, thereby forming a box, concentric rings supported on said target section for receiving a marble propelled thereto along said runway and over said obstacle, a yoke hinged to said target section side walls on the outside thereof and being adapted to be swung into parallelism with said target section so that it surrounds said target section end wall and the adjacent portions of said target section side walls, and being adapted to be swung downwardly to various positions to form legs for supporting said target section in inclined positions, and a latch for securing said sections in closed position, said yoke forming locking means for said latch when said sections are in closed position.
